UNITED STATES PATENT OFFICE.

BRYAN B. STALTER, OF HARPSTER, OHIO.

FOLDING CHAIR.

1,250,691.

Specification of Letters Patent. Patented Dec. 18, 1917.

Application filed June 4, 1917. Serial No. 172,724.

To all whom it may concern:

Be it known that I, BRYAN B. STALTER, a citizen of the United States, residing at Harpster, in the county of Wyandot, State of Ohio, have invented certain new and useful Improvements in Folding Chairs; and I do hereby declare the following to be a full, clear, and exact description of the invention, such as will enable others skilled in the art to which it appertains to make and use the same.

This invention is an improvement in chairs and has particular reference to a folding chair.

15 Chairs of the type specified in the present application are particularly adapted for use in theaters and like places and an object of the invention is to arrange the same in pairs in such a manner that an aisle may be formed between the chairs of each pair by 20 adjusting the same to their folded positions.

Another object is to provide a chair of simple and inexpensive construction which may be readily and quickly folded and unfolded to the desired positions.

25 The inventive idea involved is capable of receiving a variety of mechanical expressions, one of which, for the purpose of illustrating the invention, is shown in the accompanying drawing wherein:—

30 Figure 1 is a front elevation of a pair of chairs constructed and arranged in accordance with the invention, the same being shown in operative position.

35 Fig. 2 is a side elevation of one of the chairs in operative position.

Fig. 3 is a vertical sectional view.

Fig. 4 is a front elevation of one of the chairs in folded or inoperative position.

40 Fig. 5 is a side elevation of the chair in folded position.

Fig. 6 is a sectional view showing the manner of connecting the arm to the adjustable back section.

45 In carrying out the invention, each of the chairs is provided with a base 10 having a socket 11 at its upper end for receiving the standard 12 of the chair, a set screw 13 being employed for securing the standard in ad-

50 justed positions and arranged adjacent the socket 11 is a guide groove 14 for a purpose which will appear in the course of the description.

Each chair preferably comprises a stationary back section 15 formed integrally with the standard 12 and having connected to one

of the vertical edges thereof, by hinges 16 the adjustable back section 17 provided adjacent its free vertical edge with a supporting bracket 18 and a plate 19 having the 60 transverse slot 20 therein for a purpose to presently appear.

Preferably hinged at 21 to the bottom of the stationary back section 15 is the main adjustable seat section 22 having connected 65 thereto, by hinges 23 the auxiliary adjustable seat section 24 which, when the chair is in operative position, rests upon and is supported by the bracket 18. The main seat section 22 has pivoted thereto at 25 one end 70 of a guiding element 26 the other end of which extends into the guide slot 14 of the standard and engages the lower end thereof to aid in supporting the seat when the same is in operative position.

75 The auxiliary seat section is preferably provided at its free end with an arm 27 hinged at 28 and provided with a stud 29 extending from its inner end and adapted to engage in the slot 20 in the plate 19 when the 80 arm is in operative position and in view of the fact that the head of the stud engages between the plate and the adjustable back section 17 it will be obvious that the back and said sections of the chair may be covered 85 with any desirable material not shown. A coil spring 30 has one end connected to the bottom edge of the adjustable back section 17 and the bottom of the auxiliary seat section 24 and is adapted to assist in the folding 90 operation of the chair now to be described.

When folding the chair the arm 27 is first 95 swung inwardly about its hinges into engagement with the top of the auxiliary seat 95 section 24 and thereby disengages the stub 29 from the plate 19, after which the main and auxiliary seat sections are swung upwardly about the hinge 21 and into engagement with the back sections. The auxiliary 100 seat section is then grasped and swung about its hinges 23 to the position shown in Figs. 4 and 5 and by so adjusting this seat section it will be apparent that the spring 30 is placed under tension and when said auxiliary seat section has reached its folded 105 position the spring will be sufficiently expanded to exert a pull upon the adjustable back section to which it is connected and thereby swing said section to a position substantially at right angles to the stationary 110 back section 15.

In arranging the chairs, embodied in the present invention, in a theater or other like place the same are preferably grouped in pairs, as shown in Fig. 1, with the adjustable 5 back sections and auxiliary seat sections of the chairs of each pair adjacent each other so that when said sections are adjusted to their folded positions a space will be formed between the chairs and thus provide an aisle 10 which will facilitate the seating and exit of an audience. In view of the fact that each individual chair is provided with one arm 27 only, it is proposed to secure a stationary arm 31 to the floor and between the side 15 edges of adjacent chairs opposite those edges thereof to which the adjustable back and auxiliary sections are secured.

What is claimed is:—

1. A folding chair comprising a stationary back section, an adjustable back section hinged to one of the vertical edges thereof, a supporting bracket carried by said adjustable back section, a slotted plate also carried by said back section, a main seat section hinged to said stationary back section, an auxiliary seat section hinged to the main seat section and supported by said bracket when the chair is in operative position, an arm hingedly connected to said auxiliary seat section, and a stud carried by said arm and engaging in the slot in said plate to aid in supporting the seat sections in operative position.
2. A folding chair comprising a stationary back section, an adjustable back section hinged to one of the vertical edges thereof, a supporting bracket carried by said adjustable back section, a slotted plate also carried by said back section, a main seat section hinged to said stationary back section, an auxiliary seat section hinged to the main

seat section and supported by said bracket when the chair is in operative position, an arm hingedly connected to said auxiliary seat section, a stud carried by said arm and engaging in the slot in said plate to aid in supporting the seat sections in operative position, and a spring connection between said adjustable back section and auxiliary seat section for exerting a pull upon the former to adjust the same to folded position. 50

3. A folding chair comprising a stationary back section, an adjustable back section hinged to one of the vertical edges thereof, a supporting bracket carried by said adjustable back section, a slotted plate also carried by said back section, a main seat section hinged to said stationary back section, an auxiliary seat section hinged to the main seat section and supported by said bracket 60 when the chair is in operative position, an arm hingedly connected to said auxiliary seat section, a stud carried by said arm and engaging in the slot in said plate to aid in supporting the seat sections in operative position, a spring connection between said adjustable back section and auxiliary seat section for exerting a pull upon the former to adjust the same to folded position, a standard carried by said stationary back section, 65 a base for the chair having a socket therein for receiving said standard and also provided with a guide groove, and a guiding element pivoted to the main seat section and engageable in said groove whereby to support and brace said seat sections. 70

In testimony whereof, I affix my signature in the presence of two witnesses.

BRYAN B. STALTER.
